Des. 235,148
Patented May 20, 1975

235,148

COMBINATION BATTERY HOLDER AND BATTERY

Francis W. Rowbottam, Santa Barbara, Calif., assignor to
Elpower Corporation, Santa Ana, Calif.

Filed Mar. 21, 1974, Ser. No. 444,261

Term of patent 14 years

Int. Cl. D13—02

U.S. Cl. D26—6

FIG. 1.

FIG. 2.

FIG. 5.

FIG. 3.

FIG. 6.

FIG. 4.

FIG. 1 is an isometric view of a combination battery holder and battery embodying the new design of my invention showing the left side thereof;

FIG. 2 is an elevational view of the right side thereof;

FIG. 3 is a top plan view thereof;

FIG. 4 is a bottom plan view thereof;

FIG. 5 is a rear elevational view thereof; and

FIG. 6 is a front elevational view thereof.

I claim:

The ornamental design for a combination battery holder and battery, substantially as shown and described.
